UNITED STATES PATENT OFFICE.

GEORGE CHRISTENSON, OF JAMAICA, NEW YORK, ASSIGNOR TO H. W. JOHNS.
MANVILLE COMPANY, A CORPORATION OF NEW YORK.

PISTON-PACKING.

1,076,269.

Specification of Letters Patent.

Patented Oct. 21, 1913.

Application filed November 22, 1911. Serial No. 861,582.

To all whom it may concern:

Be it known that I, GEORGE CHRISTENSON, a citizen of the United States of America, residing at Jamaica, New York city, county 5 of Queens, State of New York, have invented certain new and useful Improvements in Piston-Packing, of which the following is a specification.

My invention relates to piston packing 10 and is specifically designed to produce an improved form of air tight piston packing for use in air brake structures.

My present invention is an improvement on that shown in my Patent No. 862,540, 15 dated August 6, 1907. The construction shown in my aforesaid patent, while sufficiently efficient for certain sizes of cylinders, encounters certain disadvantages when the attempt is made to apply it to pistons of 20 large diameter in that the packing expander ring being formed of metal of uneven thickness, it is practically difficult to form a sufficiently large ring out of highly tempered spring metal by the usual processes of drawing 25 or the like. Furthermore, it is the general opinion of those skilled in the air brake art that when large pistons are employed on cylinders which are usually placed horizontally under the cars, there is a tendency 30 for the weight of the piston to produce excessive wear on the packing at the lower side of the piston. My present invention overcomes these difficulties among others and produces a highly efficient piston packing 35 which can be made with equal ease for any size of piston and is equally efficient for all sizes.

The best form of apparatus embodying 40 my invention at present known to me is illustrated in the accompanying two sheets of drawings in which,

Figure 1 is an axial section of a cylinder and piston with parts broken away. Fig. 2 is a detail edge view of the piston follower 45 shown in Fig. 1. Fig. 3 is a plan view of the follower shown in Fig. 2. Fig. 4 is a detail perspective view of the piston packing expander ring used in my present invention, and Fig. 5 is a cross section of a modified form of piston follower.

Throughout the drawings like reference characters indicate like parts.

1 indicates the cylinder and 2 the ordinary piston head.

3 is the radial flange and 4 the upturned

flange of ordinary cup shaped packing of leather or similar material.

5 is a packing expander ring of elastic material, usually spring steel, which is formed of a strip of material of approximately even thickness throughout, bent or otherwise shaped so as to have the upturned flange 6 and the radially projecting flange 7.

8 is a piston follower of special form. This follower is usually formed of cast 65 metal and it and the piston head are so shaped that when assembled and held together by the bolts 15, 15, or other convenient means there is a circumferential recess 9 left between the piston and the follower 70 in which both the cup shaped packing and the expander ring 5 are seated. This circumferential recess is usually formed by making the outer flange 18 of the piston follower of an external diameter equal to the 75 external diameter of the piston head 2, so that both will fit snugly into the cylinder 1. The inner flange or ring 17 of the piston follower is also provided on its under face with an annular recess 10 in which the radial 80 flange 7 of the expander ring can be loosely seated when the parts are assembled, as shown in Fig. 1, and the follower forced down upon the radial flange 3 of the cup packing so as to clamp the same to the piston 85 head.

The outer and inner flanges 17 and 18 of the piston follower are either connected by a series of studs 12, 12, as shown in Fig. 2, which may be cast integral with the flanges 90 or they may be connected by a web 14, as shown in Fig. 5. In the first construction, the studs of course leave large radial openings 11, 11, between the two flanges of the follower and in the second construction 95 smaller radial openings 13, 13, may be formed by boring or coring out, as shown in Fig. 5.

16 is the pressure head of the cylinder.

In operation the cup leather has its radial 100 flange 3 firmly clamped between the piston head and follower with its upturned flange free to press against the cylinder walls. The expander ring 5 being loosely held behind it and sprung inwardly so as to have 105 its ends approximately adjacent, is free to expand by its elasticity and force the packing flange 4 smoothly and firmly against the cylinder walls. Also when the compressed air is admitted to the cylinder, it may pass 110

freely through the openings 13, 13, or 11, 11, according to which form of follower is employed and add its expansive force to the pressure holding the packing against the cylinder walls. The outer flange 18 of the piston follower when made to closely fit the cylinder walls, affords an additional bearing to support the weight of the piston when the cylinder is in a horizontal position 10 and thereby reduces the wear upon the under side of the piston head 2 and relieves the packing from the necessity of supporting any of the piston head weight.

The advantages of my invention comprise 15 the ease with which the improved form of expander ring may be made out of steel of any degree of temper (said ring being made of thin flat material, steel of any ordinary high temper can be stamped into the shape 20 shown without difficulty); the protection of the packing on both sides by piston head and follower so that dirt and gravel can not easily get to it; the increase of the bearing surfaces of the piston as a whole upon the 25 cylinder walls, and the distribution of this bearing surface upon opposite sides of the packing; and the preservation of the full effectiveness of the air pressure itself in forcing the packing against the cylinder 30 walls. Another advantage arising from the particular form of expander shown is that it may have its upturned flange 6 of any width so as to fully cover even a very wide packing without introducing any practical 35 difficulties in the formation of said expander such as would result in the effort to draw an expander of the type shown in my afore- said patent with a wide upturned flange.

Having, therefore, described my invention, I claim:

1. The combination with a piston head and a follower therefor of equal diameter, the parts being shaped to leave a circumferential recess between the piston and the follower, of a cup shaped flexible packing seated in said recess, one of the above named packing supporting elements being provided with openings to admit fluid pressure behind the packing.
2. The combination with a piston head and a follower therefor of equal diameter, the parts being shaped to leave a circumferential recess between the piston and the follower, of a cup shaped flexible packing seated in said recess, one of the above named

packing supporting elements being provided with openings to admit fluid pressure behind the packing and a discontinuous elastic packing expander ring also located in said recess behind the packing and free to expand radially independently of the piston head and follower.

3. The combination with a piston head and a follower therefor of equal diameter, the parts being shaped to leave a circumferential recess between the piston and the follower, of a cup shaped flexible packing seated in said recess, one of the above named packing supporting elements being provided with openings to admit fluid pressure behind the packing and a discontinuous elastic packing expander ring also located in said recess behind the packing, said expander ring being formed of a flat strip of spring metal bent to an L-shaped cross section with 75 abutting ends.

4. The combination with a piston head and follower of approximately equal diameters shaped to leave a circumferential recess between the two when assembled, of a cup shaped flexible packing seated in said recess, and an expander ring formed of a strip of elastic material of approximately even thickness throughout formed with an L-shaped cross section and bent into a circle 85 with abutting ends, seated within said cup shaped packing.

5. The combination with a piston head and follower of approximately equal diameters shaped to leave a circumferential recess 90 between the two when assembled, of a cup shaped flexible packing seated in said recess, and an expander ring formed of a strip of elastic material of approximately even thickness throughout formed with an L-shaped cross section and bent into a circle 95 with abutting ends, seated within said cup shaped packing, the radially projecting flange of the packing being gripped between the piston head and follower when assembled, and the radially projecting flange of the expander ring also projecting between the piston head and follower, but the latter being provided with an annular recess in which the said expander flange is loosely 105 seated.

GEOERGE CHRISTENSON.
